APPLICATING APPARATUS AND METHOD

Frank W. Britt, Jackson Heights, N. Y., assignor
to Victor Metal Products Corporation, Brook-
lyn, N. Y., a corporation of New York

Application February 9, 1939, Serial No. 255,514

5 Claims. (Cl. 91—67.4)

The present invention relates to container closures and more particularly to container closures of the cap type adapted to be used on bottles or other containers for medicines, cosmetics 5 or other mediums which are required to be drawn from the bottle or other container in small quantities and applied to a surface to be treated.

Prior constructions for fastening applicators to container closures have been generally unsatisfactory in that the applicators soon became detached from the cap, making the dispensing of the remainder of the medium within the container relatively difficult to the great chagrin of the user.

Other prior constructions involve relatively large and expensive holding means for associating the applicator with the cap. Bulky holding means have been found to be unsatisfactory as in many cases the medium within the container 20 may react with or act to rapidly deteriorate the said holding means, effecting consequent disassociation of the applicator from the cap. As combined cap-applicators have found great use in dispensing mediums of relatively low cost, it is 25 essential that the entire unit including the cap, applicator, container, etc. be of a nature to cost as little as possible. Accordingly, it is essential that the holding means for associating the cap with the applicator be of the smallest size that is 30 necessary to effect its purpose and of a relatively inexpensive material.

It is an object of the instant invention to provide a combined container closure and applicator involving a simple, novel and inexpensive 35 medium for holding the applicator to said closure.

It is a further object of the invention to provide a combined cap and applicator of relatively low cost, of a nature facilitating fabrication and permitting flexing of the applicator with respect 40 to the cap.

Other objects and the nature and advantages of the invention will be apparent from the following description taken in conjunction with the accompanying drawing, wherein:

Fig. 1 is a view partly in elevation and partly in section illustrating the construction of the combined closure and applicator;

Fig. 2 is a view partly in elevation and partly in section taken along line 2—2 of Fig. 1 and looking in the direction of the arrows;

Fig. 3 is a view in perspective of the grooved flexible socket;

Fig. 4 is a view illustrating the socket and a section of the applicator in elevation prior to their association; and,

Fig. 5 is a sectional view illustrating a cap and combined socket and applicator prior to their association.

Referring to the drawing, a container cap 10 which may be formed of any material such as for example, plastics including phenolic resinoids, urea-formaldehyde resinoids, cellulose and vinyl compounds, is provided with screw threads 11 for association with a container having corresponding threads in the usual manner. The inner central portion of the container cap 10 may be formed with a protruding tubular socket like formation 12 for receiving the upper end 13 of the applicator 14, which may be of the dropper type illustrated, the brush type, not shown, or it 15 may take any other form, and the holding means 15.

The processes involved in the formation of the container cap and the applicator do not form part of the instant invention, but the association of these two elements is material to the invention and is discussed below in detail. The holding means 15, see Fig. 3, may be fabricated of rubber, synthetic rubber such as polymerized chloro, 2, buta-diene, 1,3 known by the trade names "Duprene" and "Neoprene", or any other suitable flexible material. The holding means 15 is closed at its upper end 16 and is formed with a hollow interior 17 to receive the upper end 13 of the applicator 14. The transverse dimension of the upper portion 13 of the applicator is preferably greater than the transverse dimension of the interior 17 of the holding means 15 whereby when they are associated as suggested by Figs. 1, 2, 4 and 5, the side walls 18 of the flexible holding means 15 below the closed end 16 thereof will bulge as illustrated in Fig. 5.

The curved surface of the generally cylindrical holding means 15, see Fig. 3, is provided with grooves 19 to form a fluted outer surface capable of marked change in external configuration under compression as for example illustrated in Fig. 2, wherein the grooves 19 have been reduced to but a fraction of their size before assembly of the applicator with the cap through the medium 40 of holding means 15. The transverse dimension of the combined holding means and applicator upper end 13 is preferably greater than the transverse dimension of the interior 20 of the socket like formation 12 formed within the cap 10, 45 whereby when the combined applicator upper end 13 and holding means 15 are associated with the interior 20 of the protruding formation 12 as suggested by Fig. 5, the exterior of the side walls 18 will be materially compressed and the grooves 50 55

19, illustrated in Fig. 3, will be reduced to but a fraction of their pre-assembly dimension or they may disappear entirely.

After assembly the ball like lower end 21 of the applicator 14 may be utilized for applicating and dispensing purposes without contact with the material receiving the medium dispensed or there may be contact and sufficient stress applied to effect flexing of the applicator 14 with respect to the cap 10 as indicated by the dotted lines in Fig. 1. The resiliency of the holding means 15 permits such relative displacement of the applicator 14 while at the same time holding the said applicator securely to the cap 10.

In the assembly of the combined cap and applicator, the bulging which takes place when the upper portion 13 of the applicator rod is associated with the hollow interior 17 of the holding means 15 is more or less limited to the side walls 20 18 which are below the closed upper end 16, thereby permitting ready insertion of this sub-assembly into the hollow interior 20 of the protruding formation 12 of the cap 10. Not only does the substantially non-bulging portion 16 of the holding means 15 permit of ready insertion of the other assembly but it prevents the "pushing through" of the upper portion 13 of the applicator which would take place if the holding means 15 were simply a tube open at both ends. This 30 "pushing through" would make the insertion thereof as a sub-assembly within the relatively small hollow interior 20 of the projecting formation 12 a very difficult task. The closed end 16 of the holding means 15 therefore has a dual function, facilitating fabrication by permitting ready association of the applicator with the cap and preventing the insertion of the applicator rod into the container cap without carrying with it the holding means 15.

In accordance with the instant invention, not only is the nature of the material of which the holding means 15 is fabricated depended upon to associate the applicator with the cap but the structural formation thereof also effects this purpose and at the same time permits of greater flexing than would be possible without the said particular structural formation.

While it is contemplated that in the fabrication of combined cap-applicators in accordance with the invention that glass applicator rods of substantially uniform section be utilized, the cross sectional dimension of said glass applicator rods may vary without interfering with the ready fabrication of the cap-applicator assemblies for the fluted exterior of the holding means 15 is capable of more or less distortion than that illustrated in Fig. 2, depending on the size of the upper portion 13 of the applicator 14. This variation of cross sectional dimension of the upper portion 13 and the applicator 14 does not affect the holding properties of the holding means 15 which effects its function in a satisfactory manner by virtue of its configuration in accordance with the invention.

It is to be understood that it is within the scope of the invention to vary the nature of the materials of which the elements described are fabricated. For example, though the applicator 14 is illustrated as being of glass it may be of another suitable material such as metal or synthetic organic plastic and it is conceivable that the holding means 15 be fabricated of cork or other organic or inorganic flexible materials.

It will be obvious to those skilled in the art that various changes may be made in this device without departing from the spirit of the invention and therefore the invention is not limited to what is shown in the drawing and described in the specification but only as indicated in the appended claims.

What is claimed is:

1. A combined cap-applicator comprising a plastic container cap formed with internal screw threads and a projecting tubular formation generally concentric to said screw threads, a glass applicator, and holding means for associating said glass applicator with the interior of said tubular formation, said holding means comprising a flexible closed end cup-shaped structure having a 25 projecting portion on its exterior surface.

2. A combined cap-applicator comprising a cap having a hollow projecting formation, an applicator associated therewith, and holding means for effecting said association comprising a fluted flexible structure.

3. A combined bottle cap-applicator comprising a formed plastic cap including internal screw threads and a generally hollow cylindrical projecting formation arranged generally concentric to said threads, a glass applicator rod, rubber holding means for effecting association of the upper portion of said rod with the interior of said hollow projecting formation, said holding means comprising a generally cylindrical flexible structure closed at its upper end and formed with spaced vertical grooves on its curved surface to provide a plurality of distortable projecting strips.

4. The method of fabricating a combined applicator, flexible cup-shaped holding means, and a container cap having a hollow protruding formation comprising: inserting the upper end of the applicator into the flexible cup-shaped holding means to substantially bulge a portion thereof, inserting the thus formed sub-assembly into the hollow protruding formation of said cap, and effecting distortion of the exterior of said holding means to provide a tight flexible junction.

5. A combined cap-applicator comprising a cap having a projecting formation and an applicator associated therewith, a holding means effecting said association and comprising a rubber member having a projection on its outer surface adapted to project a predetermined distance prior to its association with the said formation of the 60 said cap and said projection adapted to be deformed subsequent to its said association.
